[57] CLAIM

The ornamental design for a vehicular van body, substantially as shown and described.

DESCRIPTION

FIG. 1 is a side elevational view of a vehicular van body showing our new design;

FIG. 2 is a top plan view thereof;

FIG. 3 is a front elevational view thereof;

FIG. 4 is a rear elevational view thereof;

FIG. 5 is a side elevational view thereof opposite to that shown in FIG. 1; and

FIG. 6 is a bottom plan view thereof.

The broken lines in the drawing are for illustrative purposes only.
